UNITED STATES PATENT OFFICE.

JAMES C. MARS, OF CHICAGO, ILLINOIS, ASSIGNOR, BY DIRECT AND MESNE ASSIGNMENTS, TO FLEUR DE LIS SPECIALTY COMPANY, OF CHICAGO, ILLINOIS, A CORPORATION OF ILLINOIS.

CREAM-MASSAGE DEVICE.

1,117,208.

Specification of Letters Patent. Patented Nov. 17, 1914.

Application filed February 21, 1913. Serial No. 749,786.

To all whom it may concern:

Be it known that I, JAMES C. MARS, a citizen of the United States, residing at Chicago, in the county of Cook and State of Illinois, have invented certain new and useful Improvements in Cream-Massage Devices, of which the following is a specification.

My invention has for its object the provision of a fountain massage device of a simple form adapted for the convenient application in an efficient manner of face or shaving cream and the like.

The invention embraces also a safety feature whereby the device can be supplied only with cream of a given quality or make. To this end the invention comprises the fountain massage instrument proper and in combination therewith a cream charging device such as a collapsible tube adapted to co-act with certain constructional features of the massage instrument whereby the supplying of the latter with cream can be accomplished only by the co-operation of the two, thus guarding against fraudulent substitution to the injury of the user and manufacturer.

In the accompanying drawings and in the description based thereon I set forth preferred and modified constructions embodying the invention which is likewise capable of embodiment in other and varied constructional forms. It will therefore be understood that the drawings and description are to be construed in an illustrative and not an unnecessarily limiting sense.

In the drawings: Figure 1 is a top plan view of the preferred form of the massage device ready for use; Fig. 2 is a side elevation of the device shown in Fig. 1; Fig. 3 is a central vertical section through the device; Fig. 4 is a detail perspective view of the handle disassociated from the pad; Fig. 5 is a side elevation of the modified construction; Fig. 6 is a top plan view of Fig. 5; and Fig. 7 is a central vertical section through the form of construction shown in Figs. 5 and 6.

Referring particularly to the form of the invention shown in Figs. 1 to 4 inclusive, the massage instrument proper comprises a massage pad 11 having upon its face rubber contact elements 12 and also with a rubber cup, the walls 13 of which inclose a recess 14 communicating at its inner extremity

with a tubular channel 15, which forms with 55 the bore 16 of a metal thimble 17 a passage-way to and beyond the back of the pad. The thimble 17 is provided at its inner end with a flange 18 preferably angular and embedded within the material of the pad at the 60 time of molding the latter. The outer end of the thimble is provided preferably with a left hand thread adapted to engage within the similarly threaded lower end of an elbow connecting element 19, the opposite 65 end of the elbow being also provided with interior left hand thread for releasable engagement with a left hand thread formed upon the nozzle 20 of a collapsible tube 21 adapted to contain the fluid or semi-fluid 70 material for the application of which the massage device is intended and which is referred to herein generally as cream. The offset converging ends 22, 22 of a wire handle are embedded as indicated in the material of the pad 11 at the time of molding the latter, the handle extending from the end walls of the pad upwardly and thence in parallel spaced relation as indicated at 75 23, 23. The spaced members 23, 23 are 80 adapted to lie on opposite sides of the cream tube 21 so that when the members 23 are grasped with the hand the tube 21 lies within the palm between said members and is protected thereby.

The device is adapted for use in the simple form above described, the cream being discharged into the pad as required by a slight pressure of the fingers upon the collapsible tube. In order, however, to provide 90 additional support for the tube 21 and to impart greater certainty to the feeding of the cream, I preferably mount upon the parallel members 23 of the handle a wire carriage 24 adapted to slide along the members 23. The carriage 24 is provided with terminal loops 25 and 26 which serve as bearings for a split key 27 the furcated portion of which is adapted to embrace the flattened end of the tube 21 and to wind the 100 same up for the purpose of expelling the cream from the opposite end. The key 27 may be of the ordinary kind, but it may also be advantageously provided with a spur 105 28 adapted to puncture the walls of the collapsed tube and thus effectually prevent re-filling.

By the provision of a left hand interior

thread upon the connection member 19, and by the adoption as a container for the cream of a collapsible tube having its nozzle similarly threaded I prevent the massage device being used in connection with any cream other than that supplied in such a container and of a given manufacture, as the collapsible tubes on the market have their nozzles universally equipped with a right hand thread. Obviously if it is desired that the massage device shall be capable of employment in connection with all kinds of cream the connecting member may be provided with a right hand thread.

15 In that form of the construction shown in Figs. 5, 6, and 7 the pad 31 having the rubber bristles 32 is equipped with a cup 33 of slightly different form but communicating as before through the passage 34 with the bore 35 of the thimble 36, the said thimble having a terminal interior left hand thread instead of exterior thread as in the former case. Here the thimble is adapted for direct engagement with the threaded 20 nozzle 37 formed upon an integral lateral extension 38 of the collapsible tube 39. In order to provide for the revolution of the tube 39 in a substantially horizontal plane in the act of screwing the nozzle 37 home in 25 the thimble 36 I provide a retaining member 40 which is substantially U-shaped, the two extremities being offset at 41 and then laterally bent and seated within ears 42 formed upon the handle 43 immediately adjacent to the pad, the opposite end of the 30 retaining member 40 corresponding to the closed end of the U is likewise offset at 44 and twisted at 45 about a pin 46 which is journaled in other ears 47 of the handle. 35 In this instance the split key 48 with its carriage 49 travels upon the retaining member 40. When it is desired to attach a tube of 40 cream to this form of the device the ends 41 of the retaining member are sprung inwardly to release them from the ears 42 and are then swung upwardly upon the pivot pin 46, the tube of cream is then connected to the pad by revolving the same and brought into a position in alignment with 45 the handle whereupon the retaining members are swung downwardly to the position shown and snapped into the ears 42. In 50 this case as in the other the key and carriage may be dispensed with but its employment 55 is found to be advantageous.

It will be understood that the massage pad instead of having rubber contact elements may be provided with bristles thus adapting the instrument for the application of soap cream to the face in the operation of 60 shaving, of medicinal preparations to the scalp and for various other toilet purposes.

I claim:

1. In a fountain massage device, a 65 sage pad provided with a passageway to its

face, a handle comprising parallel spaced members, and a collapsible cream container disposed in the space between the handle members in position to be manually grasped together with the handle and comprising a collapsible tube having a nozzle detachably connected to the passageway of the pad whereby to discharge the contents of the container through the pad onto the face thereof, substantially as described.

2. In a fountain massage device, a massage pad provided with a passageway to its face, a handle comprising parallel spaced members, a collapsible cream container disposed in the space between the handle members and comprising a collapsible tube having a nozzle detachably connected to the passageway of the pad whereby to discharge the contents of the container through the pad onto the face thereof, and means to progressively collapse the tube from the rear end, substantially as described.

3. In a fountain massage device, a massage pad provided with a passageway to its face, a handle comprising parallel spaced members, a collapsible cream container disposed in the space between the handle members and comprising a collapsible tube having a nozzle detachably connected to the passageway of the pad whereby to discharge the contents of the container through the pad onto the face thereof, and a key traveling on the handle and engaging the tube whereby to progressively wind up the tube from the rear, substantially as described.

4. In a fountain massage device, a massage pad provided with a passageway to its face, a handle comprising parallel spaced members, a collapsible cream container disposed in the space between the handle members and comprising a collapsible tube having a nozzle detachably connected to the passageway of the pad whereby to discharge the contents of the container through the pad onto the face thereof, and a key traveling on the handle and engaging the tube whereby to progressively wind up the tube from the rear, said key provided with means to puncture the tube to prevent re-use, substantially as described.

5. In a fountain massage device, a massage pad provided with a passageway to its face, a thimble seated within the pad and extending beyond the same to form a continuation of the passageway, said thimble provided with a terminal left hand thread, a handle connected to the pad and comprising substantially parallel spaced members, a collapsible cream container disposed in substantially parallel relation to the handle members and having a nozzle provided with a left hand thread, said container arranged to discharge its contents into the passageway of the thimble, substantially as described.

6. In a fountain massage device, a massage pad provided with a passageway to its face, a thimble seated within the pad and extending beyond the same to form a continuation of the passageway, said thimble provided with a terminal left hand thread, a handle connected to the pad and comprising substantially parallel spaced members, a collapsible cream container disposed in substantially parallel relation to the handle members and having a nozzle provided with a left hand thread, and a coupling member

adapted to connect the left hand thread of the nozzle with the left hand thread of the thimble, and means to progressively collapse the container whereby to discharge its contents through the coupling member to the face of the pad, substantially as described. 15
